UNITED STATES PATENT OFFICE

2,605,754

LOW-TENSION IGNITION SPARK PLUG FOR
CONDENSER DISCHARGE

Wytze Beye Smits, Voorburg, Netherlands, assignor to Smitsvonk N. V., The Hague, Netherlands, a corporation of the Netherlands

Application September 21, 1948, Serial No. 50,308
In the Netherlands October 4, 1947

20 Claims. (Cl. 123—169)

1

The present invention relates to low tension spark plugs with supported spark gap for condenser discharge.

Such spark plugs are known from the Dutch Patent No. 46,114, issued June 16, 1949. In this patent two, amongst others, of the fundamental requirements for a good operation of such spark plugs have been indicated, i. e.: a supported spark gap narrower than 0.3 mm. and the non-combustion of the carbon particles deposited upon the insulation separating the electrodes, and constituting the supported spark gap said particles promoting the spark discharge. In order to ensure a long useful life of such low tension spark plugs, the electrode material and the attachment of the electrodes to the insulation should meet certain requirements. These requirements are connected, amongst others, with the fact, that, as such spark plugs operate at low tensions, higher current intensities are to be used in order to achieve the certainty of ignition.

The object of the present invention is to prolong the useful life of the low tension spark plugs very considerably by giving the electrode members a suitable shape, on the one hand, and by connecting the electrode members to the insulation disposed in between so as to form an exchangeable solid electrode assembly, on the other hand. This permits the use of the spark plug body proper for a practically unlimited time, renovations being limited to the mere replacement of the electrode assembly. The exchangeable electrode assemblies too are shaped so as to ensure a long useful life period.

Another object of the invention is to provide a low tension spark plug with a supported spark gap of great length to facilitate the formation of a carbon deposit thereupon.

A further object of the invention is to provide a low tension spark plug with a cool supported spark gap equally to facilitate the formation of the carbon deposit thereupon.

According to the invention the spark plug mainly consists of a metallic spindle, suitably connected with the current source, which spindle is surrounded by a thin insulation layer, consisting, for example, of mica, porcelain, or any other suitable insulating material, embraced by a shell, which can be screwed into the wall of the explosion or combustion chamber. The exchangeable electrode assemblies can be fastened to the spark plug in a suitable manner and can easily be replaced by other ones. Preferably the shape of the electrode members is such, that the effective faces thereof, between which

2

creep sparks are generated, are as long as possible, in other words the developed length of the surface of the insulator separating the electrode members, which surface constitutes the supported spark gap being so great that the surface of the spark gap cannot be entirely swept by one spark. As already set out above the presence of a carbon deposit on the spark gap is desirable to facilitate the spark discharge. 5 By making the length of the spark gap greater than the breadth of the spark while the spark burns off the carbon already deposited on its path, the carbon deposit on another part of the spark gap has the possibility of building itself up during the operation of the spark plug. When the resistance of the part along which the spark occurred has increased due to the destruction of the carbon deposit and becomes greater than that of another portion of the spark gap upon 10 which the carbon deposit, meanwhile, has been formed, the sparks will transfer themselves to this new portion of the spark gap. After this has happened the first portion of the spark gap has the possibility of reconstituting a carbon layer while the carbon layer of the new spark path is destroyed by the occurring sparks. The action therefore is, in a way, a continuous cycle. Another advantage of long active faces of electrode members is a substantial increase of the 15 active life of the electrode assembly. The breadth of the spark gap gradually increases through the wear of electrode members and when it exceeds a certain value, the electrode members in the usual spark plugs either have to be reset, or the spark plug must be replaced by a new one.

Due to the special form of the electrode members according to the present invention the spark gap increases only very slowly thereby considerably prolonging the useful life of the spark plug. 20 The insulation resistance between the electrode members measured in a cold and clean state with low tensions amounts suitably to 80,000 ohms or less.

The exchangeable electrode assembly is in 25 contact, on the one hand, with the grounded external shell of the spark plug and, on the other hand, with the spindle insulated from the shell, said spindle being suitably connected with the current source. As the spindle of the spark plug has a greater diameter than the core electrode of the usual spark plug constructions, the heat concentration in the plane of contact between spindle and insulation is much 30 lower than in the usual embodiments. This permits the requirements, which the insulation as well as the fixation of the spindle in the insu-

lation must meet, to be much lower than in the usual constructions, said requirements being for the insulator to provide sufficient electrical insulation and not to develop cracks, and for the fixation to be free from gas leaks and to provide a mechanically strong connection between the insulator and the spindle. The lower the temperature, the easier it is to meet these requirements, as the difficulties increase with higher temperature.

It is equally of advantage to provide good metallic contact over large areas between the electrode assembly and the spark plug body as well as with the fastening means securing said assembly to said body. This measure together with the large cross-sections of the spindle and the outer shell of the spark plug body greatly facilitates the heat transfer from the electrode assembly to the spark plug body and further, keeping the supported spark gap cool and facilitating the formation of a carbon deposit thereupon during the operation of the spark plug.

The material of the electrode members proper has to be a good conductor. Suitable materials are silver and copper. In order to prolong the life period of the electrode members it is of particular advantage to plate their spark producing surfaces with a non-oxidizing heat resistant metal. I am well aware of the fact that it is known to provide the electrodes with a protective covering of a precious metal. What I claim is a protective covering consisting of non-precious metals, such as e. g. tungsten. It is equally possible to provide a thin layer of a non-oxidizing heat resistant material, such as, for example, tungsten, between the electrode members and the insulator.

The present invention will be further illustrated by means of the drawings showing some embodiments thereof. It should be mentioned, that the embodiments shown are only given by way of example.

In the accompanying drawings Figs. 1 and 2 show partly in longitudinal section and partly in elevation two different embodiments of the device according to the invention.

Figs. 3 and 4 show partly in elevation, partly in longitudinal section two other embodiments of the electrode assembly according to the invention.

Fig. 5 shows partly in elevation, partly in longitudinal section yet another embodiment of the invention.

Fig. 6 represents in top view the electrode assembly according to Fig. 5.

Figs. 7 and 8 show in top view two other embodiments of electrode assemblies of the same general arrangement as represented in Figs. 5 and 6.

In Fig. 1 there is shown a spindle 1 separated by the insulation layer 2 from the shell 3. One or more washer-shaped electrode bodies 4 are secured to the spark plug body, for example by means of a screw 6 or in any other suitable way. If more than one electrode assembly is applied, they are spaced, for example by means of a conductive metal ring (rings) 5, which may also form a whole with the electrode assemblies. An electrode assembly 4 consists of a flat insulating ring 9, to which along the inner and the outer circumferences electrode members 7 and 8 are fixed along the inner and outer circumferences of the ring, annular supported spark gaps 10 being provided between the electrode members. The gap 11 facing insulation 2 is kept sufficiently

wide to prevent the occurrence of sparks. When using more than one electrode assembly the shell of the spark plug is provided with holes 12 in order to form a communication of the interior space 13 with the explosion or combustion chamber. The gap or gaps 10 can be filled with gases or with insulating material to make it flush or nearly flush with the electrode members.

10 When a spark occurs it will take place across one of the spark gaps 10, the place of the spark being where the gap 10 has the lowest resistance. The electrodes 8 are suitably connected to the current source and to each other, by means of the spindle 1, the screw 6 and the rings 5, whereas the electrode members 7 are in contact with the shell 3 of the spark plug and thence with the ground.

15 The total length of the gap or gaps 10 being very great, the sparking increases the breadth of the spark gap only very slowly resulting in a long useful life period. When the gaps have become too wide, the electrode assemblies 4 can be replaced by new ones in an easy and rapid manner.

20 Fig. 2 shows another embodiment of the spark plug according to the present invention. 14 is the shell, separated, by means of the insulation layer 15, from the spindle 16. The electrode assembly 17 consists of a pile of flat electrode rings 19 and 20, separated from each other by means of the insulating layers 21. The electrode assembly 17 is fixed to the spark plug body by any appropriate means, for example, by means 25 of a screw 18. The screw 18, screwed into the spindle of the spark plug, connects suitably the upper electrode member 19 with the current source. The bottom electrode member 20 is directly pressed against the shell 14 of the spark plug and grounded. The electrode members of the same polarity (positive or negative) are interconnected by the conducting means 22, or 30 23, respectively. The spark occurs along the exterior circumference of the electrode assembly 17, in any place between any two electrode members 19 and 20. The supported spark gap corresponds to the thickness of the insulating layer 21. By an adequate adaptation of the insulating material to the electrode material it is possible 35 for the burning-in of the electrode and of the insulation to keep pace with one another. Eventually the insulation may burn in a little more than the electrode material. The burning-in of the insulation may be decelerated by giving the 40 insulation layers 21 a thickness, which increases toward the center line of the spark plug, so that, when burning-in of the insulation has taken place, the surface of the insulation exposed to the flame action has become greater. This 45 enables the electrodes now projecting to some extent to burn off more rapidly than the insulation, thereby restoring the original form. The same effect can be obtained by making the electrode thinner towards the interior.

50 Fig. 3 shows an embodiment of an electrode assembly which is in some respects similar to that represented in Fig. 2. The assembly comprises a plurality of stacked annular disk electrode members 30, 25 and 24 insulated from each other by means of insulating layers 26, alternate electrode members being connected with each other by means of the tubular extension of the electrode member 30 and the pins 29 respectively. Insulating rings 23 insulate the electrode members 55 25 from the tubular extension of the elec-

trode member 30, whereas the insulating rings 27 separate electrically the electrode members 24 from the pins 29. The electrode assembly can be removably secured to a spark plug body of the type represented in Figs. 2 or 5, for example by means of a screw similar to that represented in Fig. 5.

Fig. 4 shows another embodiment of an electrode assembly. It is constituted by a cylindrical body of insulating material 31, the outer surface whereof is provided with a double threaded groove, wherein electrically conductive material is disposed to form helical shaped electrode members. In the embodiment shown wire-shaped conductors 32, 33 are first located at the bottom of said grooves and electrically conductive material 42 is then molded into said grooves whereupon the outer surface of the electrode assembly is machined to give the electrode assembly a smooth cylindrical surface. If desired the wire-shaped conductors 32 and 33 may be omitted but I prefer the first described embodiment as it has a greater reliability.

The grooves may be given a rectangular, semi-circular, triangular or any other suitable shape according to the desired rates of the burning-off of the insulating and the electrode material.

The Figs. 5, 6, 7 and 8 show another embodiment of the electrode assembly. 39 is the spindle of the spark plug, separated from the shell 40 by means of the insulating layer 41. 38 is the attaching means of the electrode assembly, consisting of the parts 35, 36 and 37 fixed to one another. The electrode member is grounded via the shell 40 and shaped as a relatively thick disk, consisting, for example, of copper. 36 is a thin insulating layer. The electrode member 37 is connected via the attaching means 38 with the spindle of the spark plug. The electrode member 37 may consist either of a thin plate of metal, such as copper, for example, (Fig. 6), or of metal gauze (Fig. 7), or of perforated metal plate (Fig. 8), or may be formed in any other suitable way. The thickness of the electrode 37 and the thickness and composition of the insulation layer 36 are so adjusted with regard to one another, that they burn off simultaneously and regularly. This ensures a high operational certitude and a long life period. It is also possible to give this embodiment of the electrode assembly the shape of a hollow cylinder, instead of making it flat. The electrodes form the two mantle faces of the cylinder separated by an equally cylindrical insulating layer.

I claim:

1. A low voltage spark plug comprising an electrically conductive body member, an electrically conductive spindle member mounted in electrically insulated relation within said body member, an electrode assembly consisting of a plurality of annular electrode members, said members having opposing spark forming surfaces, alternate electrode members being electrically connected respectively to said body member and said spindle member, and solid insulating material positioned in the spark gaps between the opposing electrode members to form a continuous spark supporting surface, the annular spark gap thus formed having a length greater than the breadth of the spark produced, said electrode assembly being removably secured to said spindle member.

2. A low voltage spark plug comprising an electrically conductive body member, an electrically conductive spindle member mounted in electrici-

cally insulated relation within said body member, an electrode assembly removably secured to said spindle member, said assembly consisting of a plurality of electrode members having opposing spark forming surfaces, alternate electrode members being electrically connected respectively to said body member and said spindle member, and solid insulating material positioned in the spark gaps between the opposing electrode members to form a continuous spark supporting surface, the annular spark gap thus formed having a length greater than the breadth of the spark produced, both said spindle member and said body member being large relative to the insulating material of the spark plug thus to provide sufficient heat transfer to maintain low surface temperature of said electrodes and thereby to facilitate the formation upon the spark supporting surface of carbon which provides low resistance spark paths.

3. The invention of claim 1 wherein said electrode assembly is removably secured to said spindle member by a continuous joint of opposed surfaces to form a seal therebetween, thereby providing a substantially voidless connection therebetween.

4. A low voltage spark plug comprising an electrically conductive body member, an electrically conductive spindle member mounted in electrically insulated relation within said body member, an annular electrode assembly removably secured to said spindle member, said electrode assembly comprising an annular disk of insulating material having inner and outer spaced rings of conductive material thereon to form electrode members, the inner ring being electrically connected to said spindle member and the outer ring being electrically connected to said body member, the insulating surface between the opposing spaced rings being adapted to form a spark supporting surface for the deposition of carbon thereon.

5. A low voltage spark plug comprising an electrically conductive body member, an electrically conductive spindle member mounted in electrically insulated relation within said body member, a plurality of spaced annular electrode assemblies removably secured to said spindle member, each of said electrode assemblies comprising an annular disk of insulating material having inner and outer spaced rings of conductive material thereon to form electrode members, the inner ring being electrically connected to said spindle member and the outer ring being electrically connected to said body member, the insulating surface between the opposing spaced rings being adapted to form a spark supporting surface for the deposition of carbon thereon.

6. A low voltage spark plug comprising an electrically conductive body member, an electrically conductive spindle member mounted in electrically insulated relation within said body member, a plurality of spaced annular electrode assemblies removably secured to said spindle member within said body member, each of said electrode assemblies comprising an annular disk of insulating material having inner and outer spaced rings of conductive material thereon to form electrode members, the inner ring being electrically connected to said body member, a plurality of holes in said body member in the vicinity of the spaces between said spaced electrode assemblies to admit the passage of combustible gases to said spaces, the insulating surface between the opposing spaced rings being adapted to form a spark sup-

porting surface for the deposition of carbon thereon.

7. A low voltage spark plug comprising an electrically conductive body member, an electrically conductive spindle member mounted in electrically insulated relation within said body member, an electrode assembly removably secured to said spindle member, said assembly consisting of a plurality of stacked annular disk electrode members insulated from each other to form opposing spark surfaces, alternate electrode members being electrically interconnected and connected respectively to said body member and said spindle member, the solid insulating material positioned in the spark gaps between the opposing electrodes thus forming continuous spark supporting surfaces, the annular spark gap thus formed having a length greater than the breadth of the spark produced.

8. A low voltage spark plug comprising an electrically conductive body member, an electrically conductive spindle member mounted in an electrically insulated relation within said body member an electrode assembly removably secured to the electrically conductive spindle member of the spark plug and comprising a cylindrical body of insulating material, said body having a double threaded, grooved exterior surface, electrically conductive material disposed in each of the threaded grooves on said body to form helical shaped annular spark electrode members separated by the spark supporting surface of solid insulating material, each of said helical rings of conductive material being adapted to be connected to opposite terminals of a voltage source.

9. A low voltage spark plug comprising an electrically conductive body member, an electrically conductive spindle member mounted in an electrically insulated relation within said body member an electrode assembly removably secured to the electrically conductive spindle member of the spark plug and comprising a cylindrical body of insulating material, said body having a double threaded, grooved exterior surface, electrically conductive material molded in each of the threaded grooves on said body to form helical shaped annular spark gaps separated by the spark supporting surface of solid insulating material, each of said helical rings of conductive material being adapted to be connected to opposite terminals of a voltage source.

10. The invention as claimed in claim 7 wherein the insulating material between the opposing electrode members increases in width toward the interior of the body member.

11. The invention as claimed in claim 8 wherein in the insulating material separating the spark gaps increases in width toward the interior of the body member.

12. The invention of claim 7 wherein the outermost one of said disk electrode members is comprised of thin apertured metal.

13. A low voltage spark plug comprising an electrically conductive body member, an electrically conductive spindle member mounted in electrically insulated relation within said body member, a plurality of annular electrode members carried by said body and having opposing spark formula surfaces, alternate electrode members being electrically connected respectively to said body member and said spindle member, and solid insulating material positioned in the spark gaps between the opposing electrode members to form a continuous spark supporting surface

for the deposition of carbon deposits so as to have a surface resistance of less than 80,000 ohms, the annular spark gap thus formed having a length greater than the breadth of the spark produced.

14. The invention of claim 1 wherein the spark producing surfaces of the electrode members have a plating of non-oxidising heat resistant material.

15. A low voltage spark plug comprising an electrically conductive body member, an electrically conductive spindle member mounted in electrically insulated relation within said body member, an electrode assembly removably secured to the electrically conductive spindle member of the spark plug and comprising a cylindrical body of insulating material, said body having a double threaded, grooved exterior surface, wire-shaped conductors located at the bottom of each of the threaded grooves on said body and molded electrically conductive material filling said grooves flush with the cylindrical surface of said body to form helical shaped annular electrode members separated by the spark supporting surface of solid insulating material, said conductive helical rings being connected respectively to said spindle member and said body member.

16. An electrode assembly comprising a plurality of annular electrode members, said members having opposing spark forming surfaces means electrically interconnecting alternate electrode members and solid insulating material positioned in the spark gaps between the alternate electrode members to form a continuous spark supporting surface, the annular spark gap thus formed having a length greater than the breadth of the spark produced.

17. An annular electrode assembly comprising an annular disk of insulating material having inner and outer spaced rings of conductive material thereon to form electrode members, the insulating surface between the opposing spaced rings being adapted to form a spark supporting surface for the deposition of carbon thereon.

18. An electrode assembly consisting of a plurality of stacked annular disk electrode members insulated from each other to form opposing spark surfaces, the alternate electrode members being electrically interconnected, the solid insulating material positioned in the spark gaps between the opposing electrode members forming continuous spark supporting surfaces, the annular spark gap thus formed having a length greater than the breadth of the spark produced.

19. Electrode assembly comprising a cylindrical body of insulating material, said body having a double threaded, grooved exterior surface, electrically conductive material disposed in each of the threaded grooves on said body to form helical shaped annular electrode members, separated by the spark supporting surface of solid insulating material.

20. An electrode assembly comprising a cylindrical body of insulating material, said body having a double threaded, grooved exterior surface, wire-shaped conductors located at the bottom of each of the threaded grooves on said body and molded electrically conductive material filling said grooves flush with the cylindrical surface of said body, to form helical shaped annular electrode members separated by the spark supporting surface of solid insulating material.
